United States Patent Office.

JOSEPH L. SEYMOUR, OF WASHINGTON, DISTRICT OF COLUMBIA.

Design No. 4,935, dated May 23, 1871.

DESIGN FOR BUNDLES OF KINDLING-WOOD.

The Schedule referred to in these Letters Patent and making part of the same.

I, JOSEPH L. SEYMOUR, of Washington, in the District of Columbia, have invented and produced a new and original Design for Bundled Kindling-Wood, of which the following is a specification.

The nature of my design is fully represented in the accompanying drawing, to which reference is made.

Claim.
I claim as my invention—
The design for a bundle of kindling-wood, as shown.
Witnesses: JOSEPH L. SEYMOUR.

WM. THOMAS,
JOHN H. WAGGAMAN.
